UNITED STATES PATENT OFFICE.

OLEY L. LEDINGTON AND JULIUS SANDELL, OF MARQUETTE, KANSAS.

CULVERT-MOLD.

1,018,396.

Specification of Letters Patent.

Patented Feb. 20, 1912.

Application filed August 7, 1911. Serial No. 642,774.

To all whom it may concern:

Be it known that we, OLEY L. LEDINGTON and JULIUS SANDELL, citizens of the United States, residing at Marquette, in the county 5 of McPherson and State of Kansas, have invented certain new and useful Improvements in Culvert-Molds, of which the following is a specification.

Our invention relates to improvements in 10 culvert molds.

The object of our invention is to provide a culvert mold which is simple in construction, efficient in operation and which may be readily knocked down and removed from 15 the operative position after the material forming the culvert has become set.

The novel features of our invention are hereinafter fully described and claimed.

In the accompanying drawings, which 20 illustrate the preferred form of our invention, Figure 1 is a longitudinal vertical sectional view of the mold set up in operative position, on the line *c-d* of Fig. 2. Fig. 2 is an end view of the same. Fig. 3 is an enlarged cross section on the line *e-f* of Fig. 25 1, the supplemental side members being removed. Fig. 4 is a perspective view of the mold. Fig. 5 is a longitudinal sectional view on the line *a-b* of Fig. 2.

30 Similar reference characters designate similar parts.

1 and 2 designate respectively the two main side members of the mold. Secured to the inner side of the member 2 are vertical cleats 3 which are adapted to have their upper ends support one set of ends of arches 4 the other set of ends of which are adapted to be supported upon the upper ends, preferably rounded, of a plurality of 35 members 5 pivoted to the inner side of the main side member 1 by pins 6. A longitudinally movable member comprising preferably a bar 7 is pivoted by pins 8 to the members 5 above the pins 6. One end of the 40 bar 7 is pivoted to a lever 9 by a pin 10, said lever being pivoted by a pin 11 to the side member 1. A bar 12 parallel with the bar 7 is pivoted by pins 13 to the members 5 below the pins 6. The bar 12 is pivoted to 45 the lever 9 by a pin 14, the pin supporting the lever 9 being disposed between the pins 10 and 14.

To releasably lock the lever in the position shown in solid lines in Fig. 1 any suitable means may be provided. In the drawing we have shown the lever 9 provided

with a bolt 15 which is adapted to engage a notch provided in the upper side of an arcuate plate 16, which in turn is secured to the side member 1. The bolt 15 is actuated 60 by a rod 17 connected to a bell crank lever 18 pivoted to the lever 9.

One or more latch bars 19 are pivoted to the member 2 and are adapted to releasably engage eyes 20 respectively which are secured in the side member 1, for releasably bracing the members 1 and 2 in the operative position.

Secured to the bar 7 are one or more plates 21 which extend upwardly from the bar 7 70 and are disposed respectively under the latch bars 19 in such positions that when the bar 7 is moved in the proper direction to release the arches 4 from the pivoted members 5, the bars 19 will be disengaged 75 from the eyes 20.

Mounted on the arches 4 are longitudinal roof members 22, one of which, preferably the middle one, is detachably secured to the arches 4 by hooks 23 which engage eyes 24 80 secured to the arches.

Supporting the main side members 1 and 2 respectively are supplemental side members 25 and 26. Secured to the inner side member 26 are vertical cleats 27 which extend above the lower edge of the side member 2 to prevent the inward movement of the said member 2. A horizontal bar 28 is secured to the cleats 27 in a position such that the upper ends of the cleats 27 will have 90 their inner sides engaged by the bar 28, thus holding the supplemental member 26 in operative position. Secured to the inner side of the supplemental member 25 are cleats 29 which extend above the lower edge of the 95 side member 1, and are adapted to have their inner sides engaged by the bar 12 when the bar 12 is in the position shown in solid lines in Fig. 1.

Cross bars 30 are adapted to be inserted 100 between the supplemental side members 25 and 26, as shown in Figs. 1 and 5, for holding the side members 25 and 26 spaced apart in the operative positions. As shown in Fig. 3, when the supplemental side members 25 and 26 are not used, the cross bars 30 may be disposed between the main side members 1 and 2.

In the operation of our invention, the supplemental side members 25 and 26 being 110 employed, the parts having been assembled as described with the pivoted members 5

supporting the arches 4, by swinging the lever 9 to the position shown in dotted lines in Fig. 1, the pivoted members 5 are swung by the bars 7 and 12 to the positions shown in dotted lines in Fig. 1. The ends of the arches 4 which have been supported by the members 5 will now be unsupported, and the plates 21 will have released the latch bars 19. At the same time the cleats 29 will be released from the bar 12. The mold may now be collapsed and the parts withdrawn from the culvert which has been built upon the mold. The arches 4 being secured to the middle roof member 22 can all be withdrawn 15 by withdrawing said roof member.

If desired the supplemental side members 25 and 26 may be dispensed with, in which case, as stated above, the cross bars 30 are mounted between the main side members 1 20 and 2. In such case the mode of operation is the same as has been described.

We do not limit our invention to the structure shown and described, as modifications, within the scope of the appended 25 claims, may be made without departing from the spirit of our invention.

Having thus described our invention, what we claim and desire to secure by Letters Patent, is:—

- 30 1. In a culvert mold, two side members, releasable bracing means connecting the side members, a plurality of arches, means on one side member for supporting one set of ends of the arches, movable means for supporting the other set of ends of the arches, a lever, and means actuated by the lever for releasing the bracing means and simultaneously moving the movable supporting means from positions supporting the arches.
- 40 2. In a culvert mold, two side members, releasable means for connecting and bracing the side members, a plurality of arches, means on one side member for supporting one set of ends of the arches, movable members supported by the other side member for supporting the other set of ends of the arches, a longitudinally movable member for simultaneously moving the movable members from positions in which they are adapted to support the arches, means carried by the longitudinally movable member for releasing the bracing means when the longitudinally movable member is moved to withdraw the movable members from positions 55 supporting the arches, and means for longi-

tudinally moving the longitudinally movable member.

3. In a culvert mold, two main side members, a plurality of arches, two supplemental side members adapted to respectively support the main side members, upwardly extending cleats on the inner sides of the supplemental side members for engaging and holding the main side members from inward movement, means on one main side member for supporting one set of ends of the arches, movable means on the other main side member for supporting the other set of ends of the arches, and a longitudinally movable member for engaging the inner sides of the adjacent cleats and for moving said movable means from positions in which they are adapted to support the arches, the longitudinally movable member when moved to disengage the movable supporting means from the arches being disposed so as to release the adjacent cleats.

4. In a culvert mold, a main side member, a supplemental side member for supporting the main side member, cleats on the inner side of the supplemental side member for engaging and holding the main side member from inward movement, members pivoted on the main side member, and a longitudinally movable member pivoted to the pivoted members and movable to and from a position in which it will engage the inner sides of said cleats.

5. In a culvert mold, a main side member, a supplemental side member for supporting the main side member, cleats on the supplemental side member for holding the main side member from inward movement, members pivoted to the main side member for supporting arches, a longitudinally movable member connecting said pivoted members and movable to and from a position in which it will engage the inner sides of said cleats, and a lever for longitudinally moving said longitudinally movable member.

In testimony whereof we have signed our names to this specification in presence of two subscribing witnesses.

OLEY L. LEDINGTON.
JULIUS SANDELL.
